FACE PANEL FOR A CONTROL INSTRUMENT

Ronald C. Miller, Norristown, Pa., assignor to Honeywell
Inc., Minneapolis, Minn., a corporation of Delaware

Filed Aug. 11, 1966, Ser. No. 3,420

Term of patent 14 years

(Cl. D52—6)

FIG. 2

FIG. 1

FIG. 3

FIGURE 1 is a front view of a face panel for a control instrument, showing my new design.

FIGURE 2 is a front perspective view showing the face panel in an environmental use.

FIGURE 3 is an elevational view of the face panel viewed from the right side.

The reverse side of the control instrument face is conventional.

Portions of the drawing are diagonally lined to indicate transparency.

The dotted line representations illustrated in FIGURE 2 are shown for illustrative purposes only and suggest a useful manner for arranging a plurality of the face panels as shown in FIGURE 1.

The dotted line representations illustrated in FIGURE 3 represent standard casework, said broken line disclosure being for illustrative purposes only.

I claim:

The ornamental design for a face panel for a control instrument, substantially as shown and described.
